ANTOINE TORRENT, OF PARIS, FRANCE.

HAIR-CURLING IRON.

1,411,817.

Specification of Letters Patent.

Patented Apr. 4, 1922.

Application filed August 27, 1919. Serial No. 320,294.

To all whom it may concern:

Be it known that I, ANTOINE TORRENT, a citizen of Spain, and a resident of 6 Avenue Friedland, Paris, France, have invented new 5 and useful Hair-Curling Irons, of which the following is a specification.

The present invention relates to a hair curling iron consisting of two arms movable in relation to one another, characterized by 10 the fact that these arms carry combs and a toothed core or former, the curling of the hair engaged in the teeth of the combs and former enclosed between said combs, being obtained by relative movement of these two 15 members, that is to say by deformation of the originally straight lock of hair.

The annexed drawings represent by way of example two forms of construction:

Figures 1, 2, 3, 4 and 5 represent a first 20 form of construction.

Figure 1 is a side elevation of the instrument in the closed position, the upper and lower shields being in section upon their longitudinal axes:

Figure 2 is a side elevation of the instrument in the open position, the upper and lower shields being in section upon their longitudinal axes.

Fig. 3 is a plan view corresponding to 30 Figure 1, the upper shield being removed; the dotted lines indicate the deformation of the lock of hair by displacement of the core or former from left to right.

Figure 4 is a view of the instrument seen 35 from below, the lower shield being removed.

Figure 5 is a section on line 5—5 of Figure 1.

Figures 6, 7 and 8 represent a second form 40 of construction;

Figure 6 is an elevation in longitudinal section of the instrument in the open position.

Figure 7 is a horizontal section on line 7—7 of Figure 6, the cover enclosing the 45 mechanism for operating the combs being removed.

Figure 8 is a vertical cross section of the instrument in the closed position.

According to the first form of construction, the same arm carries two fixed side-combs, between which is placed a movable core or former; the reciprocating movement of the core is obtained by hand by actuating one or other of the levers provided for this 55 purpose, and the release of the hair from

the teeth of the comb and from the grooves on the core is operated by the raising of the bars parallel to the side combs, produced by the opening of the instrument.

The curling iron comprises two arms *a* 60 and *b* jointed together at the point *c*. The arm *a* consists of a plate *d* with two right-angled flanges *e* which are notched at *f* so as to form side-combs. This plate is also provided with an elongated slot *g* which serves 65 as guide to the movable core or former *h*. The latter is of semi-cylindrical shape and provided on the convex upper side with grooves *h'* corresponding to the notches *f* in the side combs; on its lower side it carries 70 two lugs *i* *i'* having rebates in which the plate *d* engages.

The displacement of the core *h* is obtained by a connecting rod *j* pivoted at one end upon the lug *i* and at the other upon a crank 75 *k* integral with a pinion *l*, the spindle *m* of which is fixed upon the plate *d*. The rotation of the pinion *l* is obtained in one or the other direction by the movement of one or other of the levers *n* and *o* carrying respectively externally and internally toothed segments; the axis of rotation *p* common to 80 these two levers is fixed to the plate *d*.

Upon the spindles *q* and *q'* journaled on the plate *d* are riveted short cranks *r* and *r'* 85 at the extremities of which are pivoted metal bars *s* parallel to the side-combs and forming coupling rods.

The axis *q* is integral with a crank *t* upon which is pivotally connected a rod *u*, of 90 which the other extremity is connected to arm *b* so that the motion of opening the arms *a* *b* produces the raising of the bars *s*.

In order to curve or wave a lock of hair, the method of operation is as follows: The 95 instrument having been first heated to a suitable temperature, the arms *a* *b* are separated and the lock of hair which it is intended to curl is introduced between them; the side bars *s* being raised, the hair can 100 then uniformly spread over the whole length of the instrument. By bringing together the two arms, the bars *s* are lowered to clear the side combs; the hair then engages in the teeth of the side combs and in the grooves 105 of the former, this being the position shown in full lines in Figure 3. By pressure upon the lower lever *n*, the core or former is displaced from left to right, whereby the lock of hair is distorted along the dotted lines 110

and given the curling or undulating movement desired.

The instrument is then opened; the hair is freed from the teeth of the comb by the elevation of the side-bars, and the instrument is moved by a distance equal to its width along the lock of hair; it is then closed again and the upper lever *o* pressed, which produces a further distortion of the 10 lock of hair by movement of the core or former from right to left. This same succession of operations is thus repeated as many times as necessary.

According to the second form of construction, one of the arms carries the side combs and the other the movable core; the reciprocatory movement of the latter is controlled automatically by the closing of the instrument and the release of the hair from the 20 combs is effected by the withdrawal of the said combs into the interior of the instrument.

The same reference letters indicate the same parts as in the first construction, the 25 new parts being designated by figures.

The lower arm *a*, consisting of a semi-cylinder, carries internally two movable combs 1 each forming a portion of a cylinder. These combs 1 are guided in their displacements by pins or screws 2 passing into slots 3 at their extremities. Each comb comprises 30 two inclined ramps 4 in which engage two pins 5 carried by a plate 6 movable at the bottom of the arm *a*; this plate 6 is guided by pins or screws 7 passing into slots 8 aligned along the centre line, and receives a reciprocating movement from a connecting rod 9, the other end of which is pivoted upon the arm *b*.

40 A semi-cylindrical cover 10, secured by screws upon the body of the arm *a* encloses the mechanism for elevating the combs.

The upper arm *b* comprises internally two longitudinal webs 11 which serve as slides 45 for the toothed former *h* supported by two transverse lugs *i* and *i'*.

The former *h* receives by means of a rod 12, a connecting rod 13 and a crank 14, a reciprocating movement from a mechanism 50 contained in a casing 15 and hereafter described.

This mechanism is arranged in such a way that at the end of the closing movement of the instrument, the core or former receives 55 a motion of translation in one direction, and that at the succeeding closure it receives a movement of the same extent in the opposite direction which restores it to its original position.

60 The mechanism comprises a rod 16 guided at the bottom of the casing 15 and operated by means of a connecting rod 17 during the opening and closing of the instrument. This rod 16 carries a lug 17' which serves to operate a crank 18 keyed upon a spindle 19

journaled in the casing 15 and upon a cross-bar 20 secured in the casing. A pin 18' limits the rotation of the spindle 19 in the direction of unwinding of a spiral spring 21 fixed on this spindle and having its other end 70 attached to the casing 15. A ratchet wheel 22 is also fixed on the spindle, the ratchet 23 being mounted upon a toothed wheel 24 loose upon the spindle 19. A spring 25 forming a stop allows rotation of the wheel 24 in 75 one direction only. A pinion 26 keyed on a shaft 27 meshes with the toothed wheel 24, and on this shaft 27 is fixed the crank 14.

A coiled spring 28, acting on the guided rod 16 causes automatically the opening of 80 the instrument.

Let it be supposed that the instrument is in the open position indicated in Figure 1; in this position the side combs 1 are lowered, the core or former *h* at the end of its movement towards the right and the spiral spring 21 unwound. On closing the instrument, the plate 6 is displaced from left to right and causes the raising of the combs by the lugs 5 engaged in the inclined ramps 4; at the same time the guided rod 16 moves from left to right carrying the crank 18 in its movement. This rotation causes the winding up of the spiral spring 21, whilst the toothed wheel 24 remains stationary, the teeth of the 95 ratchet wheel being turned in such a way that in this direction of rotation the ratchet 23 slips over the teeth of the wheel 22. At the end of the stroke of the guided rod 16 the crank 18 escapes from the lug 17. The 100 spindle 19 and the ratchet wheel revolve in the direction of the arrow carrying with them the toothed wheel 24 which is connected to the ratchet wheel 22 by the ratchet 23. This rotation produces at the same time that 105 of the pinion 26 and of the crank 14 fixed on the same spindle. The gear-ratio of the toothed wheel 24 and pinion 26 is such that for the amount of the angular movement of the crank 18 the crank 14 makes 110 a half-turn; in this way the former *h* which was at the end of its stroke to the right, travels from right to left and comes to the left end of its stroke, while the crank 18 has come back to its original position 115 against the lug 18'.

Upon opening the instrument, the side combs 1 drop, the guide rod 16 moves from right to left bringing the lug 17 again into engagement with the crank 18, which sets 120 the mechanism once more in position to operate; at the next closure, the former *h* will receive a movement from left to right.

The operation of the curling iron in accordance with this second construction is 125 similar to that of the instrument previously described, but its use is very much simplified, because after having heated the iron it is only necessary to spread the hair uniformly over the whole length of the lower 130

arm and to bring the two arms together in order to obtain the curling or undulating effect. The instrument is opened and moved by a distance equal to its width along the 5 lock of hair and re-closed; in this way the same succession of operations are repeated as often as necessary.

It will be evident that the invention is not limited to the forms of construction and the 10 details which have been described. Thus, for example, these instruments might be constructed for electrical, gas, alcohol or gaso-line heating, and any suitable mechanical, 15 pneumatic or electrical operation might be employed for raising the side bars or combs and reciprocating the core or former.

Lastly, a curling instrument in accordance with the invention can be constructed with several cores or formers, and several 20 combs arranged parallel to one another so as to allow of curling a complete length of hair at one operation.

Claims—

1. In a hair-curling iron, a pair of arms 25 movable with relation to each other, combs carried by one of said arms, a movable toothed former upon the other of said arms, and means operative during the opening 30 movement of the said arms for disengaging the hair from the combs.

2. In a hair-curling iron, a pair of arms movable with relation to each other, combs carried by one of said arms, a movable toothed former upon the other of said arms, 35 and means for automatically disengaging the hair from the combs upon the separation of said combs and former.

3. In a hair-curling iron, a pair of arms 40 movable with relation to each other, combs carried by one of said arms, a single toothed former upon the other of said arms, means for independently displacing said former in opposite directions upon the said arm, and means operative during the opening move-

ment of the said arms for disengaging the 45 hair from the combs.

4. In a hair-curling iron, a pair of arms movable with relation to each other, movable combs carried by one of said arms, a single toothed former movable upon the 50 other arm, a shield upon each arm, and means for automatically withdrawing the combs within the shields upon the separation of said combs and former.

5. In a hair-curling iron, a pair of arms 55 movable with relation to each other, movable combs carried by one of said arms, a single toothed former movable upon the other arm, a shield upon each arm, means for automatically withdrawing the combs 60 within the shields upon the separation of the combs and former, together with means for automatically imparting to the former a reciprocating movement upon the closure of the instrument.

6. In a hair-curling iron, a pair of arms 65 movable with relation to each other, movable combs carried by one of said arms, a toothed former movable upon the other arm, a shield for each of said arms, means for automatically withdrawing the combs within 70 the shields upon the opening of the device, a spring, means for stressing said spring during the closure of the instrument, means for releasing said spring at the end of the 75 closure of the instrument, a train of gears operated by said spring on its release, a crank mounted upon one of said gears, and a connecting rod between said crank and the movable former.

In testimony whereof I have signed my name to this specification.
